UNITED STATES PATENT OFFICE.

ERVIN V. SWEET, OF ATTLEBORO, MASSACHUSETTS, ASSIGNOR TO C. O. SWEET AND SON COMPANY, A CORPORATION OF MASSACHUSETTS.

DESIGN FOR A PIN, BROOCH, OR SIMILAR ARTICLE.

46,760.

Specification for Design.

Patented Dec. 8, 1914.

Application filed October 13, 1914. Serial No. 866,552. Term of patent 3½ years.

To all whom it may concern:

Be it known that I, ERVIN V. SWEET, a citizen of the United States, residing at Attleboro, in the county of Bristol and State of Massachusetts, have invented a certain new, original, and ornamental Design for a Pin, Brooch, or Similar Article, of which the following is a specification.

In the accompanying drawing which forms a part of this specification, the figure is a front elevation of a pin, brooch, or similar article embodying my new design.

I claim:

The ornamental design for a pin, brooch, or similar article, as shown.

ERVIN V. SWEET.

Witnesses:

HORATIO E. BELLows,
FREDA C. ANDERSON.
